UNITED STATES PATENT OFFICE

ERICH R. ZADEMACH, OF ELIZABETH, NEW JERSEY, ASSIGNOR TO METALWASH MACHINERY COMPANY, OF NEW YORK, N. Y., A COPARTNERSHIP COMPRISED OF HERMAN O. BOEHME, ERICH R. ZADEMACH, AND ALBERT C. NOLTE

WASHING MACHINERY

Application filed October 1, 1927. Serial No. 223,466.

This invention relates generally to washing machinery, and more particularly to such machinery of the class employed in cleaning from articles such as metalware the grease, 5 dirt and chips accumulating thereon during the processes of manufacture and use thereof.

An object of the invention is the provision, in a machine of this character, of means for thoroughly washing such work material.

10 Another object is the provision of a machine of this character so constructed and arranged that the washing liquid may be used over and over again.

15 A further object is the provision of means for separating, by sedimentation, from the washing liquid, during its passage through the machine, heavy refuse, such as chips, which have been washed from the work material.

20 A still further object is the provision of skimming means for removing from the washing liquid, during its passage through the machine, floating refuse such as oil and grease, which has been washed from the 25 work.

A still further object is the provision of means for insuring that the washing liquid, in its passage through the machine, shall be effectually heated.

30 A still further object is the provision of means for causing the washing liquid to follow a devious course in its passage through the machine, in order that such sedimentation, skimming and heating processes may be 35 carried out with certainty and thoroughness.

The following is a description of a washing machine embodying the invention in its present preferred forms; but it will be understood that various modifications and 40 changes may be made therein without departing from the spirit of the invention and without exceeding the scope of the claims.

The invention will best be understood by 45 reference to the accompanying drawings, wherein are illustrated its present preferred embodiments, and in which Fig. 1 is a sectional plan of a washing machine on the line 1—1 of Fig. 2, looking in the direction of the arrows; Fig. 2 is a sectional side elevation of 50 such machine, on the line 2—2 of Fig. 1,

looking in the direction of the arrows; Fig. 3 is a transverse section on the line 3—3 of Fig. 1, looking in the direction of the arrows; Fig. 4 is a plan of a partition and weir element embodying one feature of the invention; 55 Fig. 5 is a sectional plan of a tank embodying a modified form of the invention; and Fig. 6 is an elevation of a separation reservoir which may be employed in connection with the washing machine for salvaging valuable greases and oils employed in the processes of manufacturing the work material to be treated.

A relatively large volume of washing liquid is employed in machines of this character. 65 For example, 400 gallons of liquid per minute are passed through one such machine which is ten feet long and forty inches wide, exclusive of the side tank. The washing is, of course, most effectually accomplished 70 when the washing liquid is quite hot. It is customary to use chemical washing compounds in the water, and these compounds are expensive. For the purpose, therefore, of conserving the heat as well as the cleansing 75 chemicals in such large quantities of washing liquid, it is obviously desirable that the liquid shall be used over and over again, rather than being discharged immediately it has become contaminated. However, in 80 order that the washing operation may be successfully carried out under such conditions of continuous use of the liquid, it is necessary to provide means for removing therefrom the grease, oil, dirt, chips and 85 other refuse carried away from the work material. Some of this refuse, such as dirt, metal chips, etc. is heavier than the cleansing liquid, while other material, such as grease and oil, is lighter than the cleansing liquid. 90 It is therefore highly advantageous, in carrying out the continuous washing process, to remove both heavy and light refuse. The present invention embodies means for removing the heavy refuse by agitation and 95 sedimentation; and for removing the light refuse by agitation, flotation and skimming. The washing liquid may thus be used for long periods with minimum loss of heat—requiring only occasional replenishment of 100

small quantities of water and cleansing chemicals.

Like reference characters indicate like parts throughout the drawings.

- 5 Referring to the drawings, 1 denotes a housing, preferably constructed of sheet metal, such as steel or non-ferrous metal. Suitably journaled on the outer or inner side of said housing and actuated by any well-known means (not shown) are a plurality of rotating rolls, such as 2a, 2b, 2c, coating with an endless conveyor belt 3 to drive the latter in the direction indicated by the arrow in Fig. 2. The upper portion of each end 10 of the housing is open to permit of placing work material upon the right-hand end of the conveyor belt and of discharging the same from the left-hand end thereof. It will be understood, however, that the direction of travel of the conveyor belt may be reversed, in which case the work material will be placed upon the left-hand end of the belt and discharged from the right-hand end thereof. Suitably mounted within the housing are a plurality of pipes studded with spraying nozzles, such as 4, 5, and 6, connected, respectively, to inlet pipes, such as 4a and 6a, which pipes, in turn, are connected to a pump (not shown). The pump, through 15 its connecting pipes, draws the washing liquid from the wash tank side of the machine, and returns it under high pressure to the nozzles, from whence it is projected onto the work material carried by the conveyor belt 3.
- 20 35 As shown in Fig. 2, nozzle pipe 4 is adapted to spray downwardly, nozzle pipe 5 to spray sidewise, and nozzle pipe 6, located underneath the roller conveyor, is adapted to spray upwardly. Thus the work material, in traveling through the spraying zone, is subjected 25 to the action of a multiplicity of high-pressure jets of hot washing liquid, which liquid may, if desired, contain an alkali acting to dissolve and saponify grease and oil carried 30 by the work material.

In order that the attendants who place the work material in the machine and remove the same therefrom may not be unduly hampered by steam issuing horizontally from the openings in the ends, respectively, of the housing, there is installed at the intake end an inwardly-inclined baffle 7; and, at the discharge end, a similar baffle, 8. The action of these baffles is to deflect the steam continually rising from the body of washing liquid. Adjunctive to said baffles, respectively, are curtains, 9 and 10, extending transversely across the ends of the housing and conveniently hung to end baffles, such as 11 and 12, forming 35 the end braces of the housing. The co-operative effect of the baffles and curtains is to deflect the steam upwardly, rather than permitting it to issue horizontally from the housing into the face of the attendant. Baffle 8 40 may also serve as a return drain plate for

liquid carried by the work material upon its discharge from the conveyor belt 3.

After impinging upon the work material, the washing liquid, together with the grease, dirt, chips, etc. which have been removed thereby, falls through the conveyor belt 3 (which is preferably of the wire-mesh type) and flows by gravity down the inclined drain plate 13 (as indicated by the solid arrows in Fig. 1) to intake section 14 of a muck tank. From this intake section, the liquid, with the refuse carried thereby, flows into the first settling chamber 15 of the muck tank (Fig. 1), wherein is located the overflow and skimmer box 16, the function and mode of operation of which will be hereinafter described in detail. The flow of liquid continues from chamber 15 through strainers 17 and 18, into a second settling basin 19, also forming a part of the muck tank. Thereafter, the flow continues over a weir portion 20 of a partition member 21 (Figs. 1, 3 and 4), dividing the muck tank from the washing-liquid heating-tank section 22, through said heating-tank section to a connecting discharge-tank section, 23, through said discharge-tank section to a pump suction tank 24, through said pump suction tank to a pump suction pipe 25, to a pump (not shown), and through said pump and connecting pipes back to the spray nozzle pipes 4, 5 and 6.

Because of the large volume of washing liquid flowing down the drain plate 13, the liquid in the intake section 14 of the muck tank is violently agitated and churned, thereby intimately mixing the grease and oil with the washing liquid, subjecting the same to the action of the chemicals held in solution in said liquid, and whipping the thereby saponified material into foam (indicated in Fig. 2 by the numeral 26), which foam floats on the surface of the washing liquid. In spite of the agitation of the liquid, some of the heavy refuse, such as large metal chips (indicated in Fig. 2 by the numeral 27) is, however, precipitated in the intake section 14 of the muck tank.

As appears from Fig. 1, there is a relatively narrow opening from intake section 14 into chamber 15 of the muck tank, and this tends to restrict to the immediate vicinity of such opening the agitation of the liquid in passing through said chamber 15. Because of this decreased agitation, another and more considerable portion, 28, of the heavy refuse is precipitated in chamber 15. Overflow and skimmer box 16 (Figs. 1 and 3) is so constructed and arranged that its upper edges are operatively at the level of the washing liquid in chamber 15 and in chamber 24. As a result, the refuse floating in the form of foam on the surface of the liquid in chamber 15 continually seeps over the edges of the box, from whence it may be carried away by discharge pipe 29, connected to a sewer. The

skimming of foam from the washing liquid is facilitated by the wave action resulting from the continual rush of the large volume of liquid down the drain plate 13 and into the intake section 14 of the muck tank—such wave action extending, to a greater or lesser degree, into chamber 15.

Strainers 17 and 18 are preferably installed in such a manner that they operatively incline 10 from the vertical. They are so positioned between chamber 15 and settling basin 19 as to permit of their convenient removal for cleaning purposes through the top of said chamber 15 which chamber is operatively 15 closed by a cover 30 (Fig. 3). In the passage of the liquid through these strainers, any large particles of refuse, whether they be heavy or light, are necessarily intercepted.

It will be noted from Fig. 3 that the lower 20 portion of partition tank wall 31 is cut away, said wall extending downwardly only to a point slightly above the liquid level. As the liquid flows from the drain plate 13, it is diverted into chamber 15 by partition wall 25 32, which separates the intake section 14 of the muck tank from the settling basin portion 19 thereof. Upon entering chamber 15, it is again diverted by the left-hand, or partition, portion (Figs. 3 and 4) of the member 30 21, and caused to pass through strainers 17 and 18 and into settling basin 19.

Because of the protecting action of partition wall 32 and of the screens 17 and 18, the liquid, in its passage through settling basin 35 19, is subjected to but slight agitation, such as has hereinbefore been described as occurring in intake section 14 of the muck tank, and, to a lesser degree, in chamber 15 thereof. The strainers 17 and 18 will have removed all but the finest particles of heavy 40 refuse which has not been precipitated in chambers 14 and 15. Means are provided for insuring sedimentation of substantially all such remaining heavy refuse in settling basin 45 19. This portion of the process is carried out in the following manner: as appears from Figs. 3 and 4, the member 21 (the left-hand portion of which constitutes a liquid-level 50 partition between chamber 15 and pump suction chamber 24) has its right-hand portion cut away for a short distance below the top and for nearly the entire width of the main tank. The opening thus formed preferably 55 extends from one to three inches below said liquid level; and the portion 20 below said recess constitutes a submerged weir, over which all the liquid must flow in its passage to heating tank section 22 (Fig. 1). By thus 60 restricting the outflow to the upper portion of the settling basin 19, agitation of the liquid is minimized at this stage of its passage through the machine, and sedimentation of the remaining small particles of heavy refuse is greatly facilitated.

65 An important feature of the invention con-

sists in the provision of a vertical wall, 33, which divides the main tank into two chambers, 22 and 23, through which the liquid is forced to flow. As appears from Fig. 1, the major portion of this wall is parallel to the 70 main walls of the housing, while its right-hand end diverges from parallelism, embracing about one-half the width of the tank and closing the end of the chamber thereby formed. The inclined portion of the wall 75 thus serves as a baffle for liquid passing over the weir 20. The advantage of so inclining the end of this wall lies in the fact that it is thereby possible to employ a weir which is of a length substantially equivalent to the full 80 width of the tank. The recess above the weir may thus be relatively shallow, in order to minimize disturbance of the main body of liquid in the settling basin 19 and thereby 85 promote sedimentation; and, at the same time, because of its considerable length, the recess is of adequate cross-sectional area to permit of unobstructed flow of the large body of liquid required to pass thereover.

The vertical wall 33 has another important 90 function. In machinery of this character it has heretofore been the practice to install the heating unit for the liquid at any convenient point—irrespective of considerations involving thermal efficiency. Thus, with such a 95 heating unit (for example a number of steam coils) located at one end of a long tank, reliance must be placed largely upon the heat-conducting capacity of the liquid, the general circulation thereof, and the convection currents therein, to uniformly and adequately produce the desired heating effect upon the large mass of liquid. In the present invention, the chamber 22 is provided with heating 100 means (here shown as a plurality of steam coils, 34 and 35). The vertical wall 33 divides the main tank into a heating chamber 22 and a discharge chamber 23. In the course of 105 its continuous flow (under the urge of a suction pump) through the machine, the liquid is forced to pass through chamber 22, where it is, of course, subjected to the heating action of the coils throughout practically the entire 110 length of the chamber. The uniform and adequate heating of the liquid is thereby assured.

The lower portion of partition wall 31 is also cut away between discharge chamber 23 and pump suction chamber 24, in the same manner as hereinbefore described in relation to the portion of said wall between chamber 15 and settling basin 19. There is thus an unobstructed flow of liquid between said chambers 23 and 24. Interposed between pump suction pipe 25 and the main portion of pump suction chamber 24 are installed two vertical strainers, 35 and 36, which may be of fine-mesh wire screen and which serve to intercept 115 any small particles of refuse not either previously precipitated or intercepted by strainers 120 125 130.

17 and 18. The pump mechanism and the spraying nozzles are thereby protected from entrance of material which might tend to clog them. Because of the suction action of the 5 pump, the liquid level in chamber 24 is, during the operation of the machine, normally somewhat lower than the level in chamber 15; but when the pump is shut down, the level of course becomes the same throughout the 10 machine. This permits any refuse which may be floating on the surface of the liquid in chamber 24 to seep over the upper edge of the skimmer box 16.

15 A chute, 37, may be provided at the discharge end of the machine for receiving washed material conveyed thereto by conveyor belt 3. This chute is preferably perforated to permit of draining therethrough and onto baffle 8 any surplus liquid carried by the work 20 material.

25 It is contemplated that the sediment (indicated as 27 and 28) shall be periodically removed from the muck tank, access to said tank being obtained through cover 30 over the chamber 15.

30 The muck tank is provided with a drain pipe 38, having a valve 39 for discharging its contents into a waste pipe 40, connected to a sewer. It is thus possible to drain and 35 clean the muck tank without loss of the main body of liquid in the machine. Pump suction chamber 24 is provided with a similar drain pipe 41 and valve 42, whereby the main body of liquid may be discharged through 40 waste pipe 40 whenever, for any reason, it is found desirable so to do. In the embodiment of the invention illustrated in Figs. 1, 2, 3, 4 and 5, the floating refuse skimmed into box 16 is continuously discharged through pipe 29.

45 In the modified form of the invention illustrated in Fig. 5, there are provided a tank 1, a drain plate 13, an intake section 14 of a muck tank, a chamber 15 and an overflow and skimmer box 15, a partition and weir member 20, and heating coils 34 and 35, similar to the correspondingly numbered parts in the embodiment illustrated in Figs. 1, 2, 3 and 4. In the embodiment illustrated in Fig. 5, however, no vertical partition wall is provided, and the pump intake is connected near the discharge end of the machine. A tank 40 is provided for permitting access to the machine for cleaning purposes. This form of 50 the invention is somewhat simpler in construction and is employed where especially narrow tanks are required.

55 In drawing and otherwise treating metal, it is frequently necessary to employ as lubricants greases and oils so valuable as to render it desirable to salvage the portions thereof which adhere to the work material. When such material is to be treated, hot water alone is employed as a washing liquid, because the 60 inclusion of a strong alkali would result in

the saponification of the grease or oil. The powerful sprays of hot water wash off the grease or oil which, of course, floats on the water. In the passage of the liquid through chamber 15, the oil or grease, which, by agitation, has been brought to the surface of the water, seeps over the upper edges of the overflow and skimmer box 16. Under these conditions of operation, the lower end of pipe 29 enters a separation reservoir 41 (Fig. 6), and is not connected to outlets 41 and 38—discharging into said reservoir the skimmed grease or oil, together with any residual water carried therewith. One end of a water drain pipe, 42, enters the reservoir and projects downwardly to a point below the bottom of pipe 29 and just above the bottom of said reservoir. The floating grease or oil may be periodically drawn from the reservoir through valve 44, while the accumulated water passes out through drain pipe 42. A main discharge pipe 45, provided with a valve 46, permits of draining the entire contents of the reservoir, whenever it may be found desirable so to do. The separation reservoir 90 may be heated in order to maintain in a liquid state grease which it is sought to salvage.

95 I have described what I believe to be the best embodiments of my invention. I do not wish, however, to be confined to the embodiments shown, but what I desire to cover by Letters Patent is set forth in the appended claims.

I claim:

1. In a machine of the character described, 100 including nozzles for spraying washing liquid upon work material, in combination a drain plate for said liquid, a muck tank into which said drain plate discharges, a skimmer in said muck tank, a settling basin communicating with said muck tank, strainers between said basin and tank, a heating chamber communicating with said settling basin, a submerged weir between said heating chamber and basin, a discharge chamber communicating with said heating chamber, a partition between portions of said chambers and means communicating with said discharge chamber for circulating said washing liquid.

105 2. In a machine of the character described, the combination of a container for washing liquid comprising a muck tank, a settling basin communicating therewith, a heating chamber communicating with said settling basin, a weir between said basin and chamber maintaining the liquid in the basin and tank substantially at a predetermined level, heating coils in said chamber, a discharge chamber separated by a partition for a portion of its length from said heating chamber, a pump suction chamber communicating with said discharge chamber, strainers in said pump suction chamber and a circulating pump communicating with said last-named chamber.

3. In a machine of the character described including a conveyor for work material and nozzles for spraying washing liquid upon such work material, in combination a housing for said nozzles and conveyor, a tank for holding wash liquid in said housing, a relatively small drain receiving chamber in said housing and below said conveyor, and a sedimentation chamber in communication with said drain receiving chamber and with said tank, said sedimentation chamber being disposed externally and laterally of said housing, and being dammed off from the major portion of the tank so that it can be drained and cleaned without draining the major portion of the tank. 70
4. In a machine of the character described including a conveyor for work material and nozzles for spraying washing liquid upon such work material, in combination, a housing for said nozzles and conveyor, a tank for holding wash liquid in said housing, and a second housing disposed externally and laterally of said first named housing, said second housing having a separator chamber and an outlet chamber, means for causing used liquid to flow into said separator chamber, said separator chamber being in communication with said tank to permit the flow of liquid into said tank, and said outlet chamber being in communication with said tank and, through the tank, with the separator chamber. 85
5. In a machine of the character described, including nozzles for spraying washing liquid upon work material, in combination a housing for said nozzles, a liquid storing chamber disposed below said nozzles, a drain receiving chamber, a third chamber interposed between said first mentioned chambers, a weir partition permitting the flow of liquid thereover from said interposed chamber to said storing chamber, a drain plate disposed below said nozzles causing the used liquid to flow into said drain receiving chamber, a separator chamber disposed laterally of said housing and in communication with said drain receiving chamber and a foraminous partition between said separator chamber and said interposed chamber. 100
6. In a machine of the character described, including nozzles for spraying washing liquid upon work material, in combination a housing for said nozzles, a tank disposed below said nozzles and comprising a large liquid heating chamber, a drain receiving chamber, a third chamber interposed between said first mentioned chambers and a weir partition permitting the flow of liquid thereover from said interposed chamber to said heating chamber; a drain plate disposed below said nozzles and over said tank causing the used liquid to flow into said drain receiving chamber, a housing disposed laterally of said tank and having a separator chamber in communication with said drain receiving chamber, a foraminous partition between said separator chamber and said heating chamber, and an outlet chamber in communication with said heating chamber and disposed laterally thereof. 115
7. In a machine of the character described, including nozzles for spraying washing liquid upon work material, in combination a housing for said nozzles, a tank disposed below said nozzles and comprising a large liquid heating chamber, a drain receiving chamber, a third chamber interposed between said first mentioned chambers and a weir partition permitting the flow of liquid thereover from said interposed chamber to said heating chamber; a drain plate disposed below said nozzles and over said tank causing the used liquid to flow into said drain receiving chamber, a housing disposed laterally of said tank and having a separator chamber in communication with said drain receiving chamber, a foraminous partition between said separator chamber and said heating chamber, and an outlet chamber in communication with said heating chamber and disposed laterally thereof. 125
8. In a machine of the character described, including spraying nozzles for spraying washing liquid upon work material, in combination, a housing enclosing the sprayers, a tank in said housing for holding washing liquid, comprising a drain receiving chamber and a liquid heating chamber, a side tank of as great depth as the tank in the housing, a partition dividing the side tank into sedimentation and pump chambers, the sedimentation chamber being interposed between the drain receiving chamber and the heating chamber, a pump for taking liquid from the pump chamber and discharging it through the nozzles, and a skimmer in the sedimentation chamber comprising a waste conduit for discharging floating refuse from the system, the partition between the sedimentation and pump chambers having its upper edge disposed just a little above the level of the skimmer to prevent direct passage of liquid from the sedimentation chamber to the pump chamber when the pump is in operation, the partition, however, being of such limited height that liquid from the pump chamber may seep over the partition and be skimmed by the skimmer when the pump is stopped. 130
9. In a machine of the character described, including spraying nozzles for spraying washing liquid upon work material, in combination, a housing inclosing the sprayers, a tank in said housing for holding the washing liquid, comprising a drain receiving chamber and a liquid heating chamber, a side tank alongside the housing, the side tank being of as great depth as the tank in the hous- 1

ing, means dividing the side tank into sedimentation and pump chambers, the sedimentation chamber being interposed between the drain receiving chamber and the heating 5 chamber for taking liquid from the pump chamber and discharging it through the nozzles, and a skimmer in the side tank comprising a waste conduit, the skimmer being disposed to skim floating refuse from the sedimentation chamber and from the pump 10 chamber when the pump is stopped, and to discharge such refuse from the system.

In testimony whereof I have affixed my signature to this specification.
